(57) **CLAIM**

The ornamental design for a multi-heater, as shown and described.

DESCRIPTION

FIG. 1 is a perspective view of the multi-heater of my new design, showing an open front door and interior elements.

FIG. 2. Is a front elevational view thereof.

FIG. 3 is a back elevational view thereof.

FIG. 4 is a left side elevational view thereof.

FIG. 5 is a right side elevational view thereof.

FIG. 6 is a bottom plan view thereof; and,

FIG. 7 is a top plan view thereof.

The broken line elements in FIGS. 1 and 2, representing flames, are environmental matter and form no part of the invention.

1 Claim, 6 Drawing Sheets
